ATTORNEY

UNITED STATES PATENT OFFICE

FRITZ FISCHER, OF BERLIN, GERMANY, ASSIGNOR TO GESELLSCHAFT FUR DRAHTLOSE TELEGRAPHIE M. B. H. HALLESCHES, OF BERLIN, GERMANY, A CORPORATION OF GERMANY

ARRANGEMENT FOR THE RECEPTION OF ELECTRIC OSCILLATIONS

Application filed December 23, 1925, Serial No. 77,204, and in Germany February 17, 1925.

The present invention relates to a means for providing an exceptionally sensitive arrangement adapted for the reception of electrical oscillations.

More specifically, my invention relates to an improved means adapted for telegraphic reception on short waves.

The novel features which I believe to be characteristic of my invention are set forth with particularity in the appended claims. The invention itself, however, as to its organization and method of operation together with further objects and advantages thereof will best be understood by reference to the following description taken in connection with the accompanying drawings, in which;

Figure 1 represents an arrangement showing one preferred embodiment of my invention; and,

Figure 2 shows a modification wherein the receiving circuit is adapted to be loosely coupled to the transmitting circuit.

In Figure 1 an antenna circuit A having inductances 1, 2 and a variable condenser 3 is shown. B is a receiving circuit made up of thermionic valve R_2 of the usual three-element type having an output circuit including telephone receiver T, plate current source 15 and an input circuit which comprises the tuned circuit made up of inductance 4 and variable condenser 14 and grid condenser 12 and a grid resistance 13 all connected in well known manner. The filament current supply for tube R_2 is shown by battery 16. Circuit B is loosely coupled to inductance 1 of antenna A through coil 4. Also coupled to the antenna A through inductance 2 thereof by means of coils 5 and 6 is a second thermionic valve circuit C composed of a thermionic valve R_1 , filament current source 17, input circuit coil 6, output circuit coil 5 and a plate source g , a generator of audible frequency. Circuit C as will be noted is regeneratively coupled and is adapted to act as a transmitting circuit.

Referring to Figure 2, antenna A comprises inductance 7 and variable condenser 24. Transmitter circuit C similar to C of Figure 1 has its input and output circuit 9, 8 respectively coupled to the inductance 7 of

antenna A. Battery 23 furnishes tube R_1 with filament current as in Figure 1 and source g is adapted to serve the same function as a similar device in Figure 1. In the output of tube R_1 in series with the plate thereof there is connected a coupling winding 10 serving to couple circuit C with the input circuit 11, 18 of tube R_2 , resistance 20 and condenser 19 corresponding to and having the identical function of devices 13 and 12 of Figure 1. The translator as before is represented by T, the plate supply by 22 and the usual filament source, by 21. As will be noted Figure 2 differentiates from Figure 1 by that the receiver circuit B is loosely coupled through 10, 11 to the transmitting circuit C instead of the antenna A as in Figure 1.

Electron tube R_1 in both instances is closely coupled to the antenna with a result that there is produced a marked reduction in damping in the antenna circuit due to the retroactive coupling of the circuit C.

The device operates as follows: Circuit C is so adjusted that it is almost at the oscillation point, thus, when incoming energy strikes the antenna the transfer of energy from the antenna to circuit C causes circuit C to spill over with a result that high frequency oscillations will be generated. However, due to the plate supply g of circuit C being an alternating current source it is evident that for half of each cycle the plate of tube R_1 will be negative with a result that for that half cycle oscillations cease. The result is that the high frequency oscillations generated by tube R_1 are periodically stopped or what might be called chopped up at an audible frequency. This, of course, is equivalent to modulating the high frequency by audible frequency energy. These modulated high frequency oscillations are impressed on the circuit B through the loose coupling 1, 4 of Figure 1 or 10, 11 in Figure 2, detected and fed to the translator device T where the signals may be heard. It is evident from the foregoing that when high frequency signal energy ceases the oscillations in circuit C will also cease even though the plate returns periodically to a positive state.

A number of other forms of construction of the device are conceivable; for instance, modulation of the locally generated high frequency oscillations can be effected by varying the grid potential of the electron tube R_1 with the rhythm of an audible frequency. This feature could be accomplished by simply placing a source of audible frequency current in the grid circuit of tube R_1 , either directly or indirectly. As stated before the receiver need not be directly coupled to the antenna but as shown in Figure 2 may be loosely coupled with a local wave generator.

Another advantageous feature of the arrangement set forth conformably with the invention consists in the fact that the receiver is appreciably excited only at times when oscillations are set up in the local generator so that during the half cycles of audible frequency used for feeding the electron tube R_1 , when the anode potential is negative no generation of oscillations takes place; thus, at the same time audion tube R_2 remains unexcited. This feature of the invention insures greater freedom from disturbances of the receiving arrangement especially from atmospherics by which the antenna is excited by shock. In this scheme it is feasible to have recourse to very loose coupling of the receiver and antenna which, however, is adequately strong for reception purposes since the receiving energy is generated locally. Another advantage resides in the fact that the reception of signals is independent of variations of the incoming high frequency currents. This point is particularly important and favorable in the case where very short waves are used because what is perceived in the indicator or detector is solely the low frequency impulses which are produced by the local audible frequency oscillations.

While I have described my invention with reference to specific forms and arrangements shown for the accomplishment of my purpose it will be understood that other embodiments may be used without departing from the spirit of my invention or the scope of the appended claims.

Having now set forth the object and nature of my invention what I claim as new and useful and desire to secure by Letters Patent is:—

1. In an arrangement for the reception of electric oscillations, in combination, an antenna and a regeneratively-coupled electron tube circuit in close coupled relation with said antenna, and so arranged and adjusted that the said circuit is set into oscillation under the action of incoming signals, means to control the high frequency oscillations by low frequency oscillations of audible frequency and a receiving circuit in inductive relationship to said regeneratively-coupled electron tube circuit, said last named means also acting

upon said circuit for preventing the generation of oscillations at the end of a signal.

2. In an arrangement for the reception of electric oscillations, an antenna circuit, a regeneratively coupled electron tube circuit in close coupled relationship with said antenna, means controlled by incoming signals to set said electron tube circuit into oscillation, means comprising a source of low frequency oscillations for rendering said incoming high frequency signals audible and for rendering said regeneratively coupled circuit inoperative at the end of a signal impulse, and a receiving circuit in inductive relation to said regeneratively coupled electron tube circuit for receiving and translating said controlled signals.

3. In a device of the kind described a receiving circuit coupled to an electron tube circuit, an antenna circuit and a regeneratively coupled electron tube circuit in close coupled relationship therewith, said last named circuit being so arranged that it is set into oscillation when struck by incoming high frequency oscillations, means comprising an alternating current source of audible frequency in the plate circuit of said electron tube circuit whereby a modified wave may be set up in said circuit and received in said receiving circuit, said alternating current means also acting upon said oscillation circuit for preventing the generation of oscillations at the end of a signal.
